(57) **CLAIM**

The ornamental design for a debris scraper, as shown and described.

DESCRIPTION

FIG. 1 is a top perspective view of a debris scraper in accordance with the present design.

FIG. 2 is a top view thereof.

FIG. 3 is a bottom view thereof.

FIG. 4 is a left side view thereof.

FIG. 5 is a right side view thereof.

FIG. 6 is a front view thereof.

FIG. 7 is a back view thereof.

FIG. 8 is a bottom perspective view thereof.

FIG. 9 illustrates the debris scraper of FIG. 1 being operated by a user in an exemplary embodiment.

FIG. 10 is a front view thereof; and,

FIG. 11 illustrates the debris scraper of FIG. 1 being operated by a user in an exemplary embodiment.

The broken lines in the FIGS. show portions of the debris scraper and/or environment that form no part of the claimed design.

1 Claim, 6 Drawing Sheets
